UNITED STATES PATENT OFFICE.

FRANCES M. WELDON, OF CANTON, TEXAS.

BALING-PRESS.

No. 921,190.

Specification of Letters Patent.

Patented May 11, 1909.

Application filed February 28, 1908. Serial No. 418,258.

To all whom it may concern:

Be it known that I, FRANCES M. WELDON, a citizen of the United States, residing at Canton, in the county of Van Zandt, State 5 of Texas, have invented certain new and useful Improvements in Baling-Presses; and I do hereby declare the following to be a full, clear, and exact description of the invention, such as will enable others skilled 10 in the art to which it appertains to make and use the same.

The present invention has reference to baling presses and it aims, generally, to provide an exceedingly simple, readily- 15 operated, and effective machine of that class designed for baling hay.

More especially, however, the invention resides in the particular mechanism employed for operating the plunger, and in the 20 provision of means for bodily raising the door of the baling chamber prior to its detachment therefrom and to the removal of the bale, this latter feature being of considerable importance owing to the fact that such 25 doors, as ordinarily constructed, are so heavy and unwieldy that their disengagement from the fasteners by which they are held in place can not be effected without difficulty.

The invention will be readily understood 30 from a consideration of the following detailed description, and its preferred embodiment is illustrated in the accompanying drawings in which like parts or features, as the case may be, are designated by corresponding reference numerals in the several 35 views.

Of the said drawings:—Figure 1 is an end elevation. Fig. 2 is a longitudinal vertical section. Fig. 3 is a horizontal section 40 through the upper portion of the baling chamber, showing the guides, and the rollers carried by the sliding rod. Fig. 4 is an enlarged detail view of the door. Fig. 5 is a fragmental rear elevation of the baling 45 chamber, showing the vents.

Referring more particularly to the drawings, 1 designates, generally, the supporting base of the machine which, as shown, comprises a pair of oppositely-disposed U-shaped frames, the corresponding arms of 50 which are bolted together at their free ends and thus form the side sills of the base, while the front and rear sills thereof are formed in like manner by the eight por-

tions of said frames. The front sill carries 55 the swinging truck 2, while the rear frame is provided upon its under face with brackets in which the rear axle 3 is journaled, said axle carrying the ground wheels 4. The baling chamber, which is likewise mounted 60 upon the rear frame, comprises a pair of vertical sides 5 bolted at their lower ends to the corresponding side sills or arms of said frame, a bottom plate 6 which rests upon said sills and is likewise secured thereto, and 65 a back 7 which is bolted to the rear edges of the side and bottom plates. The upper portion of each side 5 is longitudinally slotted, as indicated by the numeral 8, in which slots travel rollers 9 secured to the opposite 70 ends of a horizontal shaft 10 which fits in a passage formed through the vertical stem portion 11 of the plunger 12. Said stem is hinged at its upper end to the adjacent end 75 of the lower member of a pair of plates 13 whose mutually-adjacent inner ends are likewise hinged together and are further provided with alining vertical slots 14 which communicate with each other and thus form a continuous slot through which one end of a 80 pitman 15 passes. The upper plate is pivoted at its upper end upon a rod 16 whose opposite ends fit in bearing openings formed through the upper ends of a pair of vertical 85 extensions 17 formed upon the tops of the chamber sides 5. The plates thus form a toggle or break-joint which is operated by the pitman 15, the end of the latter which passes through the slot 14 carrying a vertical plate 18 whose inner face bears against 90 the hinged ends of the plates 13. Plate 18 is provided with a vertical slot 19 through which the pitman end passes, said end being provided with a series of perforations in which a pin 20 is interchangeably engaged, 95 said pin fitting in a transverse groove formed in the outer face of plate 18. The bolt 38 of the hinge between the plates 13 likewise passes through one of said perforations, to connect the pitman to said plates. The opposite end of the pitman is pivoted to the bifurcated upper end of a depending operating lever 21 provided adjacent such point with perforated trunnions through which the pivot rod 22 passes, the opposite ends of 100 said rod passing through the perforated front and upper ends respectively of pairs of horizontal braces 23 and vertical braces 105

24, the lower ends of the latter being bolted to the front frame member of the base 1 while the rear ends of the former are bolted to the corresponding sides 5 of the baling chamber. A downward movement of the operating lever in the direction of the arrow, Fig. 2, will therefore break the joint between the plates 13 and raise the plunger, which latter will be lowered when upon a movement of the lever in the opposite direction.

10 The front of the baling chamber is partly open, as shown in Fig. 1, the plunger being held in place during its vertical movements by a pair of longitudinal guides 25 which 15 are secured to the inner faces of the chamber sides 5 at the front edges thereof, and extend to within a very short distance of the top edge of the door 26 which closes that portion of the chamber in which the compression takes place. This door, which is 20 completely removable from the chamber, is provided upon its front face with upper and lower cross-beams 27 and 28 which project at opposite ends beyond the corresponding 25 side edges of the door, the projecting ends of the lower beam resting upon the arms of the rear frame member of the base, while those of the upper beam rest upon the projecting ends of the horizontal cross beams 30 which are secured to the sides 5 of the chamber, the door being held against outward movement when in its closed position by blocks or shoulders 30 carried by the above-mentioned frame member, and by 35 standing pins 31 set into the beams 29, said shoulders and pins being adapted respectively, to engage the projecting ends of the beams 28 and 27.

As originally stated, the invention contemplates the provision of means for bodily raising the door 26, at the conclusion of the pressing operation, sufficiently far to release the beams carried thereby from engagement with the pins and shoulders, and to this end 40 a lever 32 is mounted upon the end sill of the rear frame member in such a manner that its forward end extends beneath the lower end of the door, as shown in Fig. 2. Said lever is provided intermediate its ends with 45 laterally projecting pins or trunnions 33 which extend through eyes 34 formed in the free upper ends of the arms of a U-shaped bracket 35 which is secured to the outer face of said end sill in whose upper face is formed 50 a transverse groove 36 which acts as a seat for the lever. The outer or handle end of the lever is elevated somewhat by reason of the slight increase in depth of said groove at its end adjacent to the door, the inner end 55 of the lever being curved upward slightly to permit the door to rest squarely thereon. The application of downward pressure upon the handle end of the lever will therefore raise the door bodily, as will be apparent.

60 65 The back 7 of the baling chamber is pro-

vided with two or more longitudinal slots 37 through which the air escapes during the pressing operation.

The swinging truck 2 carries a forwardly-extending yoke by means of which the machine is connected to a traction engine and moved bodily from place to place.

70 The operation of the machine is thought to be apparent from the foregoing and further description thereof is accordingly 75 deemed unnecessary.

What is claimed is:—

1. In a baling press, in combination, a frame; a baling chamber mounted thereon and provided with a removable door; a 80 plunger movable within the chamber; means on the press adapted to engage the top and bottom of the door, to retain the same in closed position; and means for bodily moving the door from engagement with said retaining means to permit its removal from 85 said chamber.

2. In a baling press, in combination, a frame; a baling chamber mounted thereon and provided with a vertically-movable door 90 having a cross beam at its top and bottom projecting beyond its side edges and arranged for removal therefrom; a plunger movable within the chamber; means adapted for engagement with the projecting end of 95 the cross beam to retain the same in closed position; and means for raising the door bodily into position to release the cross beam ends from engagement with said retaining 100 means, and to permit its removal from said chamber.

3. In a baling press, in combination, a frame; a baling chamber mounted thereon and provided with fixed end and front walls and a fixed bottom, a vertically-movable door 105 removably fitted in the open rear side of said baling chamber; a plunger movable within the chamber; means adapted for engagement with the door, to retain the same in closed position; and a lever carried by the frame 110 and adapted for engagement with the door to raise the latter bodily from engagement with said retaining means to permit its removal from said chamber.

4. In a baling press, in combination, a 115 frame; a baling chamber mounted thereon and provided with a vertically-movable door; means adapted for engagement with the door, to retain the same in closed position; and a member carried by the frame 120 and pivoted thereto and extending beneath the bottom of the door, for raising the same bodily, to effect its disengagement from said means.

5. In a baling press, in combination, a 125 frame; a baling chamber mounted thereon and provided with a vertically-movable door; means adapted for engagement with the door, to retain the same in closed position; a bracket secured to one of the end sills 130

of the frame; and a lever pivoted centrally to the bracket and extending at one end beneath the bottom of the door for raising the same bodily to effect its disengagement from 5 said means.

6. In a baling press, in combination, a frame; a baling chamber mounted thereon and provided with a vertically-movable door arranged for removal therefrom; a plunger 10 movable within the chamber; cross beams secured to the outer face of the door; means arranged for engagement with said beams, to retain the door in closed position, and means for bodily raising the door into 15 position to release said beams from engagement with said retaining means, to permit the removal of the door from said chamber.

7. In a baling press, in combination, a frame; a baling chamber mounted thereon 20 and provided with a vertically-movable door; cross-beams secured to the door; means adapted for engagement with said beams, to retain the door in closed position; and a member pivoted to the frame and 25 adapted for raising the door bodily, to disengage said beams from said retaining means.

8. In a baling press, in combination, a frame; a baling chamber mounted thereon 30 and provided with a vertically-movable door; upper and lower cross-beams secured to the outer face of the door and projecting at opposite ends beyond the sides of the chamber; means carried by the frame and 35 by the chamber for engagement with the ends of said beams, for retaining the door in closed position; and a lever pivoted to the frame and adapted for engagement with the lower end of the door for raising the same 40 bodily, to disengage said beams from said retaining means.

9. In a baling press, in combination, a frame; a baling chamber mounted thereon and provided with a removable door; a 45 plunger movable within said chamber; a toggle connected with the plunger stem; an operating lever connected with the toggle; means on said operating mechanism for moving the toggle joint independently of 50 the connection between said parts; means arranged for engagement with the door to retain the same in closed position; and means for bodily raising the door into position to release the same from engagement 55 with said retaining means, to permit its removal from said chamber.

10. In a baling press, in combination, a

frame; a baling chamber mounted thereon; a plunger movable in said chamber; a toggle connected with the plunger stem, and comprising a pair of plates hinged together at their mutually-adjacent ends and provided at such point with registering slots; a pitman having one end extending through said slots and pivotally connected to the bolt of 60 the hinge between said plates; a pin projecting from each side of said pitman and bearing at its ends indirectly on the opposite sides of said toggle levers, to relieve the pivot pin from strain when the plunger is 65 in action; and an operating lever connected to the opposite end of the pitman.

11. In a baling press, in combination, a frame; a baling chamber mounted thereon; a plunger movable in said chamber; a toggle connected with the plunger stem, and comprising a pair of plates hinged together 75 on their inner sides at their mutually-adjacent ends and provided at such point with registering slots; a pitman having one end 80 extending through said slots and pivotally connected to the bolt of the hinge between said plates; a plate secured to said pitman end on the outer sides of the pitman plates and adapted to bear against the outer face of 85 said plates when the pitman is moved in the direction for compression to relieve the hinge from strain; and an operating lever connected to the opposite end of the pitman.

12. In a baling press, in combination, a frame; a baling chamber mounted thereon and including side members provided with alining longitudinal slots; a vertically-movable door carried by the chamber; means adapted for engagement with the door, to 90 retain the same in closed position; a plunger movable within the chamber and provided with a horizontal rod having its opposite ends extending through said slots; a roller 95 secured to each end of said rod and adapted to travel in said slots; a toggle connected to the plunger stem; an operating lever connected with the toggle and a member pivoted to the frame and adapted for engagement with the door, to raise the same bodily 105 and effect its disengagement from said retaining means.

In testimony whereof, I affix my signature, in presence of two witnesses.

FRANCES M. WELDON.
